(57) **CLAIM**

We claim the ornamental design for a light fixture, as shown and described.

DESCRIPTION

FIG. 1 is a perspective view of a light fixture showing our new design.

FIG. 2 is another perspective view of the light fixture shown in FIG. 1.

FIG. 3 is a first side view of the light fixture shown in FIG. 1.

FIG. 4 is a second side view of the light fixture shown in FIG. 1.

FIG. 5 is a top plan view of the light fixture shown in FIG. 1.

FIG. 6 is a bottom plan view of the light fixture shown in FIG. 1; and,

FIG. 7 is a front end view of the light fixture shown in FIG. 1.

The dot-dot broken lines shown in the drawings illustrate portions of the light fixture that form no part of the claimed design. The drawings contain a dot-dash symbolic break, which forms no part of the claimed design. The portion between the break lines forms no part of the claimed design. The drawings also contain dot-dash broken lines representing boundaries of the claimed design and which form no part of the claimed design.
